ELECTRIC SWITCH HANDLE

Henry J. Blakeslee, Marlboro, Conn., assignor to
The States Company, Hartford, Conn., a Connecticut
statute corporation

Application September 13, 1938, Serial No. 229,679

2 Claims. (Cl. 200—172)

This invention relates to the handles of knife blade switches, and more particularly to the handles of the blades of multiple pole switches of this class.

5 A plurality of circuit conductors, both solid wire and stranded wire conductors, for electrical light and power installations, are commonly incased in metallic or non-metallic sheaths and brought to switches in the form of cables, the 10 conductors being separated from each other by rubber or woven or braided insulating coverings. The insulating coverings are variously colored or provided with strands of different colors in order that they may be distinguished from each other. 15 and the circuits properly connected to the switches.

The object of the present invention is the provision of simple, cheap and readily applied handles for switch blades which will give a visual indication of the arrangement of conductor connections that must be made in order that the circuits correctly function.

In attaining this object the switch operating handles are made of two or more complementary 25 members of insulating material which are clamped to opposite sides of the swinging ends of the blades. These members are made in quantities and are variously colored, and as desired are applied to the different blades in combinations of colors that will correspond to the identifying markings of the several circuit conductors to be connected and thus indicate how the circuit conductors should be connected to the switches.

The invention is illustrated in the accompanying 30 drawing as embodied in a four-pole single-throw knife switch of common construction.

Fig. 1 is a plan view of such a switch.

Fig. 2 is a side view of the same.

Fig. 3 is a view on larger scale of an end of a 40 blade of the switch with one member of the handle removed.

Fig. 4 is a section on plane denoted by dotted line 4—4 on Fig. 3.

Fig. 5 is a section illustrating a manner in 45 which two handles may be connected so that two blades may be opened and closed together.

The switch illustrated has four switch blades 1, 2, 3, 4 that are pivoted to conducting ears 5 which have conducting lugs 6 with terminal binding 50 screws 7, that are mounted on the insulating base 8. The free ends of the blades are adapted to be swung into and out of engagement with conducting ears 9 that have conducting lugs 10 and terminal binding screws 11.

55 The blade handles illustrated are made up of

two complementary members 12 and 13 of insulating material. These members may have any desired outline and one member preferably has a tubular boss 14 that projects through an opening in the blade into a recess in the other member. The members are held together and clamped to opposite sides of the blade by a screw 15 that has a head 16 at one end and a nut 17 at the other end, the boss 14 insulating the blade from the screw. If desired handles may be connected by filling tubes 18 and held together by long screws 19, as shown in Fig. 5, recesses being formed in the outer faces of the handle members for receiving the ends of the separating tubes. The handle members are made in different colors, 10 the colors preferably being those which are used to distinguish the circuits of so-called coded cables.

The drawing illustrates the handle of the switch blade 1 as composed of two members, one 20 black and the other white; the handle of the blade 2 as composed of two members, one red and the other black; the handle of the blade 3 as composed of two members, one green and the other white, and the handle of the blade 4 as 25 composed of two members, one yellow and the other green. These or any other desired combinations of colors can be used.

With the handle members combined as illustrated, the terminal 21 of a black and white conductor would be connected in circuit with blade 1; the terminal 22 of a red and black conductor would be connected in circuit with blade 2; the terminal 23 of a green and white conductor would be connected in circuit with blade 3; and the terminal 24 of a yellow and green conductor would be connected in circuit with blade 4.

By employing the method described the conductor terminals can be correctly connected to one side of a switch and the corresponding terminals can be correctly connected to the opposite side of the switch, without any experimentation, for the combinations of colors of the handle members indicate at a glance the necessary connections to be made to establish the required current paths. This is particularly valuable where the switches are used in connection with meters, as are many of this type of switches.

The handle members may be made in large quantities of a variety of colors, and may be attached to the switch blades according to the cables with which they are to be used. With the construction described the blades can be finished polished or plated before the handle pieces are applied.

The invention is not limited to a four-pole switch nor to the exact combination of colors for the handle members which is illustrated, nor need the handle members be combined in contrasting colors as, when desired they could be combined so that each handle would present a solid color, without departing from the invention. Other means than pigment colors may be used for contrasting the several handle members.

10 The invention claimed is:

1. In a switching means for a system of conductors having a plurality of wires, each of which is identified by two color markings for facilitating correct electrical connections, a plurality of switch blades one for each wire, and an individual handle for each switch blade composed of detachable connected members, said detachable handle members being composed of insulating material, the respective colors of said members being identical with the color markings of the wire which is to be associated therewith.
- 15 2. A switch for a system of conductors having a plurality of identified wires connected to devices which demand correct connection of con-

ductors thereto and which require at times interruption of the electrical circuits leading thereto, said identified wires being distinguished from one another by color markings, comprising a plurality of pairs of terminals insulated one from another, a plurality of switch blades of which each is pivoted to one terminal in a pair and is conductively engageable with the other terminal of a pair, said pluralities including a pair of terminals and a switch blade for each identified wire, and a plurality of handles including one for each blade; each said handle being composed of detachable insulating members of colors identical with the color markings for the corresponding identified wire, said detachable insulating members being interengaged with one another and with the corresponding switch blade to provide a protecting, enclosing, insulating handle structure around the end of the blade, and means for securing said members upon the switch blade, said securing means passing through the blade and being spaced therefrom by an interposed portion of the insulating handle structure.
